TV LAMP

Francis A. Schafer, 2916 Riverside Drive, McHenry, Ill.

Filed June 16, 1965, Ser. No. 85,764

Term of patent 14 years

(Cl. D48—20)

FIGURE 1 is a front elevational view of a TV lamp showing my new design;

FIGURE 2 is a rear elevational view thereof;

FIGURE 3 is a top plan view thereof; and

FIGURE 4 is a side elevational view thereof, the opposite side being substantially a mirror image of the side shown.

The dominant features of my design reside in the portions shown in full lines. The broken line showing of an upwardly projecting outline in FIG. 1 represents any selected background object or arrangement adapted to be supported by the lamp and is for illustrative purposes only.

I claim:

The ornamental design for a TV lamp, substantially as shown and described.
